[57] CLAIM

The ornamental design for a tubular food container, as shown and described.

DESCRIPTION

FIG. 1 is a perspective view of a tubular food container showing my new design; with the inner tray partially received in the container body; the broken line showing of a tear strip is for illustrative purpose and forms no part of the claimed design;

FIG. 2 is a front elevational view thereof; shown in fully assembled condition; the rear elevational view being a mirror image thereof;

FIG. 3 is a left side elevational view of FIG. 2; the right side elevational view being a mirror image thereof;

FIG. 4 is a top plan view of FIG. 2;

FIG. 5 is a bottom plan view of FIG. 2;

FIG. 6 is a perspective view of an inner tray; shown separately for clarity;

FIG. 7 is a left side elevational view of FIG. 6; the right side elevational view being a mirror image thereof;

FIG. 8 is a front elevational view of FIG. 6;

FIG. 9 is a rear elevational view of FIG. 6;

FIG. 10 is top plan view of FIG. 6;

FIG. 11 is a bottom plan view of FIG. 6;

FIG. 12 is a typical elevational view of a second embodiment of a tubular food container;

FIG. 13 is a top plan view of FIG. 12;

FIG. 14 is a bottom plan view of FIG. 12;

FIG. 15 is a left side elevational view of the inner tray of FIG. 12; shown separately for clarity; the right side elevational view being a mirror image thereof;

FIG. 16 is a front elevational view of FIG. 15;

FIG. 17 is a rear elevational view of FIG. 15;

FIG. 18 is a top plan view of FIG. 15;

FIG. 19 is a bottom plan view of FIG. 15; and,
